UNITED STATES PATENT OFFICE.

OSBORN B. HALL, OF MALDEN, MASSACHUSETTS.

METAL POST.

SPECIFICATION forming part of Letters Patent No. 412,498, dated October 8, 1889.

Application filed July 31, 1889. Serial No. 319,295. (No model.)

To all whom it may concern:

Be it known that I, OSBORN B. HALL, of Malden, in the county of Middlesex and State of Massachusetts, have invented a new and 5 useful Improvement in Metal Posts, which will, in connection with the accompanying drawings, be hereinafter fully described, and specifically defined in the appended claims.

In said drawings, Figure 1 is a side elevation showing a metal post embodying my invention. Fig. 2 is an enlarged longitudinal vertical section taken through the lower portion of the post shown in Fig. 1 on line X. Fig. 3 shows an enlarged modification of Fig. 15 1. Fig. 4 is a section taken on line Z, Fig. 3. Fig. 5 is an enlarged sectional elevation showing the upper portion of the post shown in Fig. 1. Fig. 6 is an enlarged section taken on line W, Fig. 1.

20 This invention relates to the metal posts which are placed near the outer edge of the portion of streets that are traveled by vehicles, to support the short wires extended across the street, and upon which the "trolley-wires," so called, are arranged to conduct an 25 electric current to be utilized in propelling street-cars upon tracks beneath the last-named wire; and the invention consists in features of novelty, which will, in connection 30 with the drawings, be hereinafter pointed out, and specified in the claims.

Referring again to the said drawings, A represents a cast-metal base which is inserted in the earth to the extent shown in Fig. 1, 35 where B represents the surface of the earth or sidewalk in which the post is placed. From base A rises the single tube or column C, which terminates at the top in the head d, oval in plan, and in which are secured by 40 screw-threading the tubes or rods e, the central one of which may, as shown in Fig. 2, be inserted in a hole that communicates directly with the axial passage in tube C. The upper ends of tubes e are screw-threaded in coupling f, in the upper side of which are in like 45 manner secured the tubes or rods g, which at their upper end are in like manner secured in cap h. The cross-street wire is shown at k, and in Fig. 1 it is shown as extended from 50 post to post across the street. As a constant tension must be maintained on wires k, and

as the posts are by the slight yielding of the earth liable to yield laterally under pressure, it is desirable to provide some means to insure such tension upon the wire without the 55 constant care that is now necessary; and to effect such result I interlock between tubes g the weight q, to move freely up and down, and I attach the wire to the weight by means of the short interposed section of wire rope, 60 (marked l,) one end of which is attached to wire k, and the other to an eye secured to the weight, as shown, said rope passing over truck i, loosely mounted on pivot j, which is supported in ears n, formed upon coupling h, 65 the pivot being so arranged that the rope above the weight is tangential to the periphery of the truck. Said wire k may be secured to the posts on the opposite side of the street by means of an eye p, formed in cap h, as 70 shown at the right in Fig. 1, or in any desired manner. The avoidupois of weight q will necessarily be sufficient to hold taut wire k with its maximum load or strain, and as it is always possible that the support of 75 the weight may suddenly give way through defects or breakage in the wire or rope, and as casualties might occur by the falling of the weight to the sidewalk, therefore the interlocking of the weight in tubes g is of es- 80 sential value and importance, as the weight can only fall to coupling f, where it is entirely accessible for replacement in connection with the wire, while if the weight were arranged in a post tubular in its entire 85 length the falling of the weight would place it beyond reach or recovery.

Base A may be formed with the wall b, either with or without the openings c through the same, as shown in Figs. 1 and 2; or it may 90 be formed, as shown in Figs. 3 and 4, with a smaller central tube having radial flanges s, which, with the tube, are formed integral with base-plate a, and when so formed the flanges that are in a plane at right angles to the line 95 of strain upon the post through wire k should be wider than are the flanges that are in the line of such strain, as the former-mentioned flanges are the principal resistants against deflection of the post from a vertical position. 100

The column C, instead of being formed integral with base A and head d, may be of

thick wrought-metal pipe duly secured in the base and head, as shown in Fig. 3.

- The advantage gained by forming the lower portion of the post with but a single pipe or column C of a height to bring head d above the tallest pedestrian (as the column shown in Fig. 1 represents a height of twenty-seven feet) is the fact that by so doing the post occupies no more of the sidewalk than does the ordinary post, while by forming the upper sections with a plurality of rods or tubes in each section much less metal is required than if the post consisted of a single tube in each section.
- 15 I do not claim herein forming metal posts in sections with a plurality of rods or tubes in the same section, with couplings to receive the ends of the several sections or groups of pipes, as the pending application, Serial No. 20 317,893, filed by me July 18, 1889, is for such a post; but

What I do claim is—

1. A post formed with a suitable base, a single column or tube rising from said base

to the requisite height and terminating with 25 a head formed to receive a plurality of rods or tubes, and one or more sections above said head, having a plurality of tubes or rods in each section, substantially as specified.

2. A metal post formed with a suitable 30 base and subdivided into lengths or sections, the lower section being formed of a single tube or column, and the other and upper lengths being formed with a plurality of tubes or rods in each length, said several 35 lengths being coupled together, in manner substantially as specified.

3. A metal post provided with a sheave or truck, pivoted and arranged in manner substantially as specified, and a weight arranged 40 in and to be guided and supported by the post and to coact with said sheave, substantially in manner as specified.

OSBORN B. HALL.
